Isaac D. Thrift
Belted Patent

The schedule referred to in the Belter Patent and making part of the same containing a description in the words of the said Isaac D. Thrift himself of his improvement for sawing, mounting, & polishing marble & other stone.

To all whom these presents shall come. Be it known that I Isaac D. Thrift of Philadelphia and State of Pennsylvania have invented a new & useful machine or improvement on the straight saw for sawing marble or other kinds of stone & that the following is a full & exact description of the said machine as invented by me. I first have a frame of wood or iron of any size about the middle of this frame, there posts standing on a horizontal or perpendicular at any height you may require. I then have a frame for my saws running in a groove or iron easily attached to the frame. I have a rod of iron or wood which is attached to a crank above the frame of the saw; at one end of this there is a pulley of wood for the belt to give motion to the crank & saw frame, in a horizontal line, or an inclined plane. There a road way for a carriage to move on with weights or catch wheels, which has the marble on and move up to the saw, over the marble there is a hopper with sand and water with conductors to lead to the saw on the top of the stone and runs directly into the saw teeth. The saw moving up and down by the rod attached to the crank as may be worked by a rach and cog wheel. These saws may be made of iron, brass or copper, or a composition of metal. Prefer copper for the saws. For mounting the same principle as the sawing for polishing I have the buff placed on the place of the saw and move by the same principle as above. These mechanics may be worked by hand, horse, water, or steam power.
